UNITED STATES PATENT OFFICE.

HULDREICH EGLI, OF BALTIMORE, MARYLAND.

OYSTER-SHUCKING MACHINE.

Application filed April 18, 1922. Serial No. 555,097.

To all whom it may concern:

Be it known that I, HULDREICH EGLI, a citizen of Switzerland, residing at Baltimore, in the State of Maryland, have invented new and useful Improvements in Oyster-Shucking Machines; and I do hereby declare the following to be a full, clear, and exact description of the same, reference being had to the accompanying drawings forming part 10 of this specification.

This invention relates to oyster shucking machines and more particularly to a machine adapted to operate automatically on the oysters from the point of manually placing the oyster in the machine in a certain position to the stage where the closing muscles have been severed and the meats of the oysters extracted from between the opened shells and the meats deposited in a suitable 20 container, leaving the empty shells only to be later removed from the machine.

An object of the invention is to provide rapidity in the opening of the shells and removal of the meats from between the shells, 25 and to provide maximum simplicity of parts and of movements of the various parts from the beginning to the end of the cycle of operations.

A further object is to provide a machine 30 that is practically continuous and automatic in its operation; that will operate on all sizes and grades of oysters effectively without adjustment of the machine and without liability of breakage of any of the parts; 35 and that will enable large quantities of oysters to be quickly shucked with a minimum expenditure of labor and at a minimum cost.

With these and other objects in view, the invention consists in certain combinations 40 and arrangements of parts as will more fully appear in the following specification, the novel features thereof being particularly pointed out in the appended claims.

In the accompanying drawings—

45 Figure 1 is a plan view of the machine; portions of the upper part of the machine being shown broken away to better illustrate interior portions;

Fig. 2 is a vertical sectional view taken 50 transversely of the machine but showing the right hand portion of the machine in elevation. Some of the duplicate parts of the

mechanism are omitted from this view to avoid confusion;

Figs. 3 and 4 are detail views of a pair of 55 muscle severing knives and one of the wedges for opening the oyster shells;

Fig. 5 is a somewhat enlarged detail view of said wedge and knives;

Fig. 6 is a sectional view on line 6—6 of 60 Fig. 5;

Fig. 7 is a detail view of a portion of one of the housings for the knives;

Fig. 8 is a perspective view of one of the 65 sections of one of the knives;

Fig. 9 is a detail view of a portion of the operating connections for actuating the oyster positioning clamp; and

Fig. 10 is a detail sectional view showing 70 the mounting of the wedge sections.

As a general outline of the machine adapted for illustrating the preferred embodiment of the present invention, a table 10 is rotatably mounted on a post 11, said table having mounted thereon the several mechanisms 75 for positioning the oysters in the machine, opening the shells of the oysters, then severing the closing muscles of the oysters and then extracting the oyster meats from between the shells, the meats being deposited 80 in a suitable container.

The post 11 for the table extends through the base 12 of the machine, the hub 13 of the table 10 being rotatably mounted on the upper end of said post. Rotary motion is imparted to the table from an operating shaft 14 extending upwardly through the base 12, a bushing being provided in the base for said shaft, and said shaft being supported adjacent its upper end in a bracket 15 projecting 85 from the post 11. A pinion 16 mounted on the upper end of shaft 14 meshes with a gear 17 formed on the hub 13 of the table, the speed of rotation of shaft 14 and the relative sizes of the pinion 16 and gear 17 being 90 such that the table 10 will revolve at the rate of approximately three revolutions per minute.

The table 10 is comparatively large and arranged in circular formation around the 100 edge of the table is a plurality of sets of mechanisms for shucking the oysters. Any desired number of these sets of mechanisms may be provided, twelve being shown in the

accompanying drawings, but as all sets of the mechanisms are of like construction the following detailed description will be limited to the preferred form of construction of one set.

Slidably mounted in circular grooves 18 on opposite sides of an opening 19 in the table 10 is a pair of wedge holders 21. The wedge 22 is composed of two sections, one attached to each of the wedge holders 21, the two sections when moved into contact with each other presenting the appearance of an inverted V. The wedge sections are adapted to be moved towards and away from each other, these operating means consisting of a stationary cam 23 fixed on the upper end of the post 11. In addition to constituting a part of the wedge actuating connections, said cam 23 also serves as a locking ring for retaining the table 10 on said post. A radially movable rod 24 slidably mounted in suitable bearings provided on the table has a cam roller 25 journaled in its inner end engaging cam 23 and at its outer end said rod 24 is connected to the wedge plates 20 by arms 26, the connections between the arms, plates and rod being such as to permit the outer ends of said arms to be moved towards and away from each other.

A spring 27 interposed between one of the bearing brackets 28 of the rod 24 and a collar 29 adjustably secured on said rod, tends to urge the rod radially inward at the cam roller 25 against the cam 23. When the roller 25 is on the low portion of the cam, the outer ends of arms 26, together with the wedge sections, will be moved towards each other but when said roller engages the high portion of the cam, said arms and wedge sections will be separated. As will be later described, this separation of the wedge sections takes place after the wedge has been inserted in between the oyster shells and is for the purpose of opening the shell of the oyster.

To support the shells, when opened, from their exterior, a bell crank lever 30, provided on one of its arms with a pin 31 adapted to engage the shell, is pivoted on the table on each side of the rod 24. The other arm of each lever is pivoted to a link 32 which in turn is connected at its inner end to the rod 24 whereby when the rod is moved outward to separate the shells the supporting pins 31 will be moved towards each other and brought into contact with the shells. To compensate for shells of varying thicknesses, springs 33 are coiled around the links 32 between collars 34 adjustably secured on said links and the bell crank lever arms to which said links are connected so that should the oyster be rather thick and the movement of pins 31 resisted before rod 24 and links 32 have reached the limit

of their outward movement, the tension of springs 33 will be overcome and, the links being slidably mounted in the bell crank lever arms, said links will be free to move independently of the bell crank levers.

70

The edge of the shell, at the mouth of the oyster, is preliminarily broken off and the oyster then manually placed in the machine in position to present the cracked edge and mouth to the wedge 22, the oyster being held in this position by suitable clamping means. Although this clamping means may be varied in its detail construction, one form that has proven satisfactory and that is of simple but durable construction, is shown in the accompanying drawing and comprises a comparatively long clamping bar 40 slidably mounted in an aperture in table 10 and in a bracket 41 attached to the knife housing hereinafter described. Fixed to the upper end of said bar 40, above the table, is a laterally extending plate 42 in which is slidably mounted a stem 43 provided with an enlarged head 44 to prevent its downward displacement. At its lower end the stem 43 carries a clamping plate 45 having a recess therein, in its lower face, for reception of the hinged end of the shells. A spiral spring 46 on the stem 43 intermediate the plates 42, 45 tends to force the latter plate downward towards wedge 22, while the entire clamping device is adapted to be urged downwardly by a heavy coil spring 47 surrounding bar 40 and interposed between the under side of table 10 and a collar 48 on the bar.

75

Below bracket 41, and adjacent its lower end, bar 40 is provided with a cam roller 49 adapted to cooperate with a stationary cam 50 on the base 12. At a certain point in the operation of the machine, as will be later described, said cam engages the cam roller 49 and forces the bar 40 together with the plates 42 and 45 upward. It is at this time, with plate 45 elevated, that the oyster is inserted in the machine against wedge 22, the spiral spring 46 holding the oyster in place until cam roller 49 passes off cam 50. Then spring 47 is free to force the bar 40 and plates 43, 45 down, the pressure exerted by said spring being sufficient to cause the wedge 22 to partially enter the mouth of the oyster.

80

After the oyster has been opened the closing muscle is severed, this being accomplished by cutting knives carried on the under side of the table 10. In the illustration of the preferred embodiment of the invention, there are two knives 60, 61 for each wedge and clamp. Said knives are carried on blocks 62 slidably mounted in ways 63 formed in a knife housing 64 attached to the table by a bracket 65. The knives are normally held with their cutting edges below the table and wedge sections by a spring 130

66 secured at its lower end to a depending portion 67 of the knife housing and attached at its upper end to the knives. Any desired means of attachment of the spring and 5 knives may be utilized, the preferred form however, consisting of a cross pin 68 attached to the spring and engaging lugs 69 formed on each of the knife blocks 62. The 10 ends of the pin 68 project into vertical slots 70 in the side walls of the knife housing 64, thus steadyng the movement of the knives while, at the same time, permitting them to reciprocate toward and away from the table.

15 Knife 60 has a lateral projection 71 that projects through a second vertical slot 72 in the knife housing and slidably mounted in an opening in said projection 71 is an operating rod 73. At its lower end rod 73 is 20 provided with a cam roller 74, a rather heavy spring 84 being interposed between the lower end of the operating rod and projection 71. After the oyster has been 25 fully opened by wedge 22, cam roller 74 comes into engagement with a stationary cam 75 on base 12 and through the connections just described pushes the knife upward between the spaced wedge sections, through 30 opening 19 and between the opened oyster shells and severs one end of the closing muscle from one side of the shell.

The other knife 61 is provided with similar operating connections, to wit, a projection 76 having a bearing therein for an 35 operating rod 77 with a spring 78 surrounding said rod. The cam roller 79 on the lower end of said rod cooperates with a second cam 80 on the base 12 but it will be noted that cams 75 and 80 are positioned 40 relatively to one another to allow knife 60 to be withdrawn below the table by spring 66 before knife 61 is advanced to sever the closing muscle from the opposite side of the shell.

45 The resistance of springs 84 and 78 on rods 73 and 77 is such that, normally, the rods and knives will move upward when the cam rollers 74 and 79 ride up on cams 75 and 80 but if either knife should encounter an 50 obstacle, say for instance the hinged end of a comparatively small oyster, the pressure of the spring of that particular knife will be overcome, resulting in the spring being compressed and the rod sliding freely in its upper bearing without any tendency to 55 further advance the knife. This feature renders the machine capable of operating on oysters of varying sizes without liability of breakage of any of the parts or operating 60 connections.

Thus far there have been described the mechanism for positioning the oyster in the machine; the mechanism for opening the shell and the mechanism for severing the 65 closing muscle from the interior walls of the

oyster shell. After this last step has been performed suitable mechanism is brought into operation to extract the severed meat from between the opened shell. As each pair of knives has its own extracting mechanism, only one extractor and its operation will be described.

70 Slidably mounted on the underside of table 10 and movable radially thereof is an extractor 90 having its outer end turned 75 up as at 91, the outer edge of said upturned end portion having teeth 92 formed thereon. Normally, said extractor 90 is held radially inward in a position on the inner side of the oyster by a spring 93 suitably attached to said extractor and the hub 13.

80 After the oyster shell is opened and both ends of the closing muscle severed, the extractor is adapted to be moved radially 85 outward, through between the parted shells carrying on its serrated edge 92 the oyster meat, the meat dropping off the extractor at the edge of the table into a receptacle (not shown). The actuating connections for the 90 extractor consist of a bell crank lever 94 pivoted on the under side of the table and to one side of the extractor, one end of the lever 94 being free and the other arm 95 being attached loosely, as by a pin and slot 95 connection, to the extractor.

At the proper point in the rotation of the 100 table the free end of the bell crank lever 94 is brought into contact with a stationary pin 96. The free end of lever 94 is momentarily held stationary by pin 96 while the table continues to advance and the lever turns on its pivot with the result that the other end throws the extractor radially outward. After the free end of the lever is 105 disengaged from pin 96 by the continued rotation of the table, the spring 93 will return the extractor to its normal position.

The pin 96 is slidably mounted in vertically disposed bearings 97, 98 in a tubular 110 supporting member 99 mounted in brackets 100 extending from the post 11. Said pin 96 is normally held in position to engage the bell crank lever 94 by a spring 101 surrounding the pin and positioned between a 115 stop 102 carried on the member 99 and a collar 103 on the pin, the upward movement of the pin being limited by collar 103 coming in engagement with bearing 97.

In order, however, to prevent the operation 120 of the extractor in the event no oyster is in the clamp, a cam 104 carried on a lateral projection 105 on the clamping rod 40 is adapted to engage a cam roller 106 journaled in a projection on the extractor operating pin 96. As will be evident, if there is no oyster in the clamp said clamp with its rod 40 will be thrust downward by spring 47 and this movement of the rod 40 will bring the cam 104 down to a position where 125 130

it will engage and push down the cam roller 106 as the table rotates. The downward movement of cam roller 106 will, of course, depress pin 96 to a point where it cannot engage the lever 94. The length of cam 104 is such that cam roller 106 and pin 96 are released immediately after the free end of lever 94 has passed the pin and the latter will be returned by spring 101 to its normal elevated position in time to engage the next succeeding extractor lever.

To prevent injury to the knives 60, 61 by coming in contact with gripping pins 31 if there is no oyster in the clamp, a spacer block 110 is fixed in clamping rod 40 where it will be brought down to a position to engage the arms of bell crank levers 30 when said clamping rod is abnormally depressed by its spring. In other words, if there is no oyster in the clamp, the only parts of the machine that will fully operate will be the wedges which will be separated as usual to permit the knives to be moved upwardly through the opening 19.

Having particularly described the several parts of each set of shucking mechanisms, the various operations of the machine will now be set forth in the order in which they are performed.

While each clamp plate 45 is elevated by cam 50 and roller 49 on the lower end of rod 40, an oyster is placed in the machine manually between the plate 45 and the corresponding wedge 22 in position to present its mount to the wedge, it being understood, as before mentioned, that the edge portion of the shell adjacent the mouth has been previously broken off. As the cam roller 49 passes off said cam, the clamping plate together with the oyster is forced downward by spring 47. While the oyster is being forced downward, the wedge sections are abutting each other due to cam roller 25 being on the low portion of cam 23 and the wedge enters the oyster mouth a slight distance, after which the cam roller 25 moves up on the high portion of cam 23 and forces the wedge sections apart. This opens up the oyster shell on its hinged end, the radial movement of rods 24 caused by cam 23 simultaneously effecting a closing movement of the gripping pins 31 to grip the opened shell on its exterior opposite the point of engagement of the wedge sections with the interior of the shell.

While the opened oysters are thus supported between the pins 31 and wedge sections, roller 74 on knife operating rod 73 rides up on cam 75 and knife 60 is projected upward through between the opened wedge sections and the opening 19 in the table, between the shells and severs the closing muscle from one side. After that end is severed, roller 74 passes out of engagement with cam 75, spring 66 becomes active,

and knife 60 is returned to its normal position. Knife 61 is then similarly projected upward by cam 80 and roller 79 to sever the remaining end of the muscle and is subsequently returned by the spring 66.

The oyster meat is then free to be removed from between the shells and immediately after roller 79 passes off cam 80 and knife 61 is retracted, the free end of bell crank lever 94 is brought into engagement with the stationary pin 96 and the extractor 90 is thrust out radially of the table, carrying with it the meat.

The several sets of mechanisms successively performs these operations as they are carried around by the rotating table and as the table can be made to carry as many sets of mechanisms as can be fed manually, or the speed of rotation of the table increased, the capacity of the machine is limited only by the ability of the operator to feed it.

While, in the preferred construction, certain parts are described as stationary and their cooperating parts movable, it is quite evident that such construction might readily be varied without departing from the spirit of this invention.

What is claimed is:

1. In an oyster shucking machine, the combination of a rotatable table, sectional wedges carried by the table, means for positioning an oyster with its mouth on the wedges, said positioning means being movable toward the wedges for forcing the wedges into the mouth of the oyster, means for moving the wedge sections apart for separating the shells, and means for severing the closing muscles of the oyster.

2. In an oyster shucking machine, the combination of a rotatable table, a sectional wedge, means for forcing said wedge sections into the mouth of an oyster, said means and wedge sections being movable toward each other, and means for separating said wedge sections for forcing open the oyster shell.

3. In an oyster shucking machine, the combination of a sectional wedge, means for forcing said wedge sections into the mouth of an oyster, means for separating the wedge sections to open the shell, and means movable between the separated wedge sections for severing the closing muscles of the oyster.

4. In an oyster shucking machine, the combination of a rotary table, a sectional wedge, means for clamping an oyster in position with its mouth on the wedge, said clamping means being movable toward the wedge for forcing the wedge sections into the oyster mouth, means for moving said wedge sections apart to open the shell, means for severing the closing muscles of the oyster, and means for extracting the oyster meat from between the shells.

5. In an oyster shucking machine, the combination of a sectional wedge, means for clamping an oyster in position with its mouth on the wedge and forcing said wedge 5 sections into its mouth, means for separating said wedge sections to open the oyster shell, and knives movable between the opened wedge sections and between the opened shells for severing the closing muscles of the 10 oyster.

6. In an oyster shucking machine, the combination of a sectional wedge, means for clamping an oyster in position with its mouth on the wedge and forcing said wedge 15 sections into its mouth, means for separating said wedge sections to open the oyster shell, knives movable between the spaced wedge sections and between the opened oyster shells for severing the closing muscles 20 of the oyster, means for extracting the meat from between the shell, and means for returning said wedge sections, knives, and extracting means to their normal positions.

7. In an oyster shucking machine, the combination of a table, a sectional wedge adapted to enter the mouth of the oyster, means for separating the wedge sections to open the oyster shell, a pair of knives normally positioned below the table, and means for 30 projecting the knives into the opened oyster shell and severing the closing muscles of the oyster.

8. In an oyster shucking machine, the combination of a table, a sectional wedge adapted to enter the mouth of the oyster, means for separating the wedge sections to open the oyster shell, a pair of knives normally positioned below the table, means for projecting the knives into the opened oyster 40 shell and severing the closing muscles of the oyster, means for retracting the knives and means for bringing the wedge sections together.

9. In an oyster shucking machine, the combination of a rotatable table, mechanism 45 for rotating said table, a sectional wedge adapted to enter the mouth of the oyster, means for separating the wedge sections to open the oyster shell, a pair of knives normally positioned below the table, means for projecting the knives into the opened oyster shell for severing the closing muscles of the oyster, and means for extracting the meat 50 from between the opened shell.

55 10. In an oyster shucking machine, the combination of a table, a sectional wedge adapted to enter the mouth of the oyster, means for separating the wedge sections to open the oyster shell, a pair of knives normally positioned below the table, means for projecting the knives into the opened oyster shell for severing the closing muscles of the oyster, a meat extractor, means for actuating the extractor and returning it to its normal 60 position, and means for rendering said

extractor inoperative when the machine is running idle.

11. In an oyster shucking machine, the combination of a rotatable table, a sectional wedge adapted to enter the mouth of the oyster, means for separating the wedge sections to open the oyster shell, a pair of knives, means for projecting the knives between the separated wedge sections into the opened oyster shell for severing the closing 70 muscles of the oyster, means for supporting the opened shells from the exterior of their sides and against the wedge sections.

12. In an oyster shucking machine, the combination of a rotatable table, a series of 75 sectional wedges slidably mounted in the table, a corresponding number of clamps for clamping the oysters against said wedges and forcing the wedges into the mouths of the oysters, a corresponding series of knives, 80 means for separating the wedge sections to open the oysters, means for advancing the knives to sever the closing muscles of the oysters, and means for restoring said wedge sections and knives to their normal positions. 85

13. In an oyster shucking machine, the combination of a rotatable table, a series of 90 sectional wedges carried on the table, a corresponding number of clamps for clamping the oysters against the wedges and forcing said wedges into the mouths of the oysters, a corresponding series of knives, 95 means for separating the wedge sections to open the oyster shells, means for advancing the knives to sever the closing muscles of the oysters, means for restoring the wedge sections and knives to their normal positions, means for extracting the oyster meat from between the shells, and means for rendering said extracting means inoperative 100 when the machine is running idle.

14. In an oyster shucking machine, the combination of a rotatable table, a series of 105 sectional wedges slidably mounted in the table, a corresponding number of clamps for clamping the oysters against the wedges and forcing said wedges into the mouths of the oysters, means for separating the wedge sections to open the oysters shells, means 110 adapted to be projected in between the opened shells for severing the closing muscles of the oyster, and means for restoring the severing means and the wedge sections to their normal positions. 115

15. In an oyster shucking machine, the combination of a rotatable table, a series of 120 sectional wedges slidably mounted in the table, a corresponding number of clamps carried by the table for clamping the oysters against the wedges and forcing said wedges into the mouths of the oysters, a corresponding series of knives, 125 means for separating the wedge sections to open the oyster shells, means for advancing the knives to sever the

130

closing muscles of the oysters, means interposed in the knife operating connections for taking up the motion imparted to the knives, whereby oysters of varying sizes may be operated upon, and means for returning the wedge sections and knives to their normal positions.

16. In an oyster shucking machine, the combination of a rotary table, a series of 10 clamping devices for positioning the oysters on the table, slidably mounted means for preliminarily opening the oysters and subsequently spreading the shells of the oyster apart, a series of knives arranged in pairs, 15 means for actuating each pair of knives for severing the closing muscles of the oyster, and means for extracting the meats from the shells.

17. In an oyster shucking machine, the 20 combination of a table, a series of slidably mounted wedges, a corresponding number of clamps each adapted to position an oyster on one of the wedges, means for moving the respective clamps and wedges together to partially open the oyster shells, means for actuating the wedges to fully open the shells, a corresponding number of pairs of knives, and means for advancing the knives into the 25 opened shells to sever the closing muscles of the oyster.

18. In an oyster shucking machine, the combination of a rotary table, a series of wedges, a corresponding number of clamps each adapted to position an oyster against 35 one of the wedges, means for moving the respective clamps and wedges towards one another to force the wedge into the mouth of the oyster, means for actuating the wedges to fully open the oyster, a pair of knives for 40 each wedge and clamp, means for projecting one knife of each pair into the opened shells and then withdrawing said knife, and means for subsequently advancing and retracting the other knife of each of said pairs of 45 knives.

19. In an oyster shucking machine, the combination of a rotary table, a series of sectional wedges, a corresponding number of oyster holding clamps each adapted to 50 position an oyster on one of the wedges, means for moving the clamp towards the wedge to force the wedge sections into the oyster, means for successively separating the sections of each wedge to fully open the shells, a pair of knives for each wedge, and means for successively projecting each pair 55 of knives into the opened oyster shells to sever the closing muscles of the oysters.

20. In an oyster shucking machine, the 60 combination of a rotary table, a series of sectional wedges, a corresponding number of clamps for positioning the oysters against the wedges, means for moving the clamps toward the wedges to partially open the 65 shells, means for successively separating the

sections of the wedges to fully open the shells, a corresponding series of pairs of knives, means for successively projecting the pairs of knives into the oysters to sever the closing muscles of the latter, a corresponding 70 number of meat extractors, and means for successively actuating the extractors after the closing muscles have been severed to extract the meats from the shells.

21. In an oyster shucking machine, the 75 combination of a rotatably mounted table, mechanism for rotating the table, a series of sectional wedges carried on the table, a series of clamps, means for moving the clamps towards and away from the wedges, 80 means for moving the wedge sections apart, a series of knife housings carried by the table, a pair of knives slidably mounted in each housing, a pair of actuating rods for each pair of knives, rollers mounted on the 85 actuating rods, and stationary cams adapted to successively engage said rollers subsequent to the separation of the respective wedge sections for severing the closing muscles of the oysters.

22. In an oyster shucking machine, the 90 combination of a post, a table rotatably mounted on said post, a series of wedges carried on the table each comprising a pair of transversely movable sections, a series of 95 clamps movable towards and away from the wedges, a stationary cam mounted on the post, a radially movable rod for each of said wedges, connecting arms pivotally connected to the respective rods and wedge sections, 100 a roller journaled on the inner end of each rod, said rollers engaging the stationary cam, whereby a radial outward movement of the rods will move the wedge sections away from each other, a pair of knives for 105 each of the wedges, and means for projecting the knives of each pair into the oyster shells after the wedge sections and shells are separated.

23. In an oyster shucking machine, the 110 combination of a post, a table rotatably mounted on said post, a series of wedges carried on the table each comprising a pair of transversely movable sections, a series of 115 clamps movable towards and away from the wedges, a stationary cam mounted on the post, a radially movable rod for each of the wedges, connecting arms pivotally connected to the respective rods and wedge sections, a roller journaled in the inner end of each rod 120 and engaging the stationary cam, said radially movable rods and connecting arms being positioned between the wedges and said cam whereby a radial outward movement of the rods will move the wedge sections away 125 from each other, a series of knife housings carried by the table, a pair of knives slidably mounted in each housing, a pair of actuating rods for the knives of each pair of knives, rollers mounted on the knife actuati- 130

ing rods, and stationary cams adapted to successively engage the knife actuating rod rollers subsequent to the separation of the wedge sections.

- 5 24. In an oyster shucking machine, the combination of a post, a table rotatably mounted on the post, a series of sectional wedges, means for clamping an oyster against each of the wedges, means for moving the wedge sections apart to open the oyster shells, a pair of knives slidably mounted below each wedge, a lateral projection carried by each knife, an actuating rod loosely mounted in each of said projections, an abutment on each rod, a spring on each rod interposed between the projections and abutments, a roller on each rod, and stationary cams adapted to engage said rollers. 10
- 10 25. In an oyster shucking machine, the combination of a post, a rotatable table on the post, a series of wedges carried on the table each comprising a pair of transversely movable sections, a series of clamps movable towards the wedges, a stationary cam mounted on the post, a radially movable rod for each of the wedges, connecting arms pivotally connected to the respective rods and wedge sections, a roller journaled in the inner end of each rod and engaging the stationary cam, said radially movable arms and rods being positioned between the cam and wedges whereby a radial outward movement of the rods will move the wedge sections away from each other, pins controlled by the radially movable rods adapted to engage and grip the opened oyster shells on their exteriors opposite the point of engagement of the wedge sections with the shells, a pair of knives for each wedge section and means for actuating the knives to sever the closing muscles of the oysters. 15
- 15 26. In an oyster shucking machine, the combination of a post, a table rotatably mounted on the post, a series of wedges carried on the table each comprising a pair of transversely movable sections, a series of clamps movable towards and away from the wedges, a cam mounted on the post, a radially movable rod for each of the wedges, connecting arms pivotally connected to the respective arms and wedge sections, a roller journaled in the inner end of each rod and engaging said cam, said radially movable rods and arms being positioned between the cam and wedges, gripping pins controlled by the radially movable rods adapted to engage the oyster shells on their exteriors, slidably mounted knives for severing the closing muscles of the oysters, and means for returning the knives, wedge sections and gripping pins to their normal positions. 20
- 20 27. In an oyster shucking machine, the combination of a rotatable table, a series of wedges, a corresponding number of clamps
- movable towards the wedges for clamping oysters against the wedges, slidably mounted knives, means for projecting the knives into the opened oysters for severing the closing muscles of the oysters, an extractor for each wedge comprising a member movable between the opened oyster shells, a bell crank lever connected to each extractor, a slidably mounted post beneath the table yieldingly held in position to engage the bell crank levers, a roller carried on the post, a series of cams normally held out of engagement with said roller, and means operative upon an abnormal movement of the clamps towards the wedges for moving the cams into position to engage said roller and depress the post, whereby said post will be moved out of position to engage the bell crank levers of the extractors in the absence of an oyster between one of the clamps and the corresponding wedge. 25
- 25 28. In an oyster shucking machine, the combination of oyster positioning means, movable members adapted to be moved apart for opening the oyster shell, and knives movable between the spaced opening members for severing the closing muscle of the oyster. 30
- 30 29. In an oyster shucking machine, the combination of oyster positioning means, slidably mounted shell opening members, means for sliding said members apart and knives for severing the closing muscle of the oyster. 35
- 35 30. In an oyster shucking machine, the combination of oyster positioning means, slidably mounted shell opening members, means for sliding said members apart and knives movable between the separated opening members for severing the closing muscle of the oyster. 40
- 40 31. In an oyster shucking machine, the combination with the supporting table having an opening therein, of oyster positioning means on one side of the table, means for opening the oyster shells, and muscle severing means located on the opposite side of the table and movable through the table opening to sever the oyster muscle. 45
- 45 32. In an oyster shucking machine, the combination of the shell opening wedges, oyster positioning means movable toward the wedges for passing the oysters against the wedges, means for actuating the wedges to open the oyster, and knives for severing the closing muscle of the oyster. 50
- 50 33. In an oyster shucking machine, the combination of a table having an opening therein, shell opening means movably positioned in said opening, oyster positioning means, and muscle severing knives. 55
- 55 34. In an oyster shucking machine, the combination of a table having an opening therein, shell opening means movably positioned in said opening, oyster positioning means, and muscle severing means movable

toward the table opening for severing the oyster muscle.

35. In an oyster shucking machine, the combination of a table having an opening therein, shell opening means, oyster positioning means and muscle severing means, said oyster positioning means and said muscle severing means each being movable toward the table opening.

36. In an oyster shucking machine, the combination of a table, means for opening the oyster shells, means for positioning the oysters on said opening means, and means for severing the closing muscles of the oysters, said positioning and severing means being located on opposite sides of said table.

HULDREICH EGLI.
